Des. 187,257
Patented Feb. 23, 1960

187,257

COMBINED BED AND CHEST UNIT

Thomas J. Hackett, Secretary, Md.

Application October 7, 1958, Serial No. 52,890

Term of patent 14 years

(Cl. D5—4)

Figure 1 is a front perspective view of my new design for a combined bed and chest unit.

Figure 2 is a top plan view.

Figure 3 is an end view.

The end not shown is like the end shown while the back of the article is plain and unornamented.

I claim:

The ornamental design of a combined bed and chest unit, as shown and described.
